Daniel E. Paris and N. F. Wedder, of Troy, N.Y.
assign to

Daniel E. Paris, aforesaid.

Letters Patent No. 1878-Dated Dec 1st 1868.

Design for Stove Plates.

The schedule referred to in these Letters Patent and making part of the same.

To all whom it may concern:

Be it known that we, Daniel E. Paris and N. F. Wedder, each of the City of Troy, in the County of Rensselaer and State of New York, have jointly invented or produced a new and original ornamental design for stove castings; and we do hereby declare that the following is a full and exact description thereof, reference being had to the annexed photographic drawings in which Fig. 1 shows a stove door, and Fig. 2, a stove leg, cast with our said ornamental design.

This new ornamental design for stove castings consists of a three-lobed pendant, $\times \times \times$, suspended within, and by a stem η from the middle of the arched top ζ , of a pinnate border moulding $a.a.$ around a sunken panel having immediately around the pendant $\times \times \times$, a pitted ground $b.b.$ outside of which latter is a plain field $c.c.$ extended to the border moulding $a.a.$ and with the pitted ground $b.b.$ conformed approximately in outline to the border moulding $a.a.$ and pendant $\times \times \times$; all the said parts being shaped and disposed together so as to appear as represented by the annexed photographic drawings.

What we claim as new and of our joint invention or production, and desire to secure by Letters Patent, is the above described ornamental design for stove plates or castings.
